UNITED STATES PATENT OFFICE.

ALEXANDER JAMESON, OF INDIANAPOLIS, INDIANA, ASSIGNOR TO F. R. HENSHAW,
TRUSTEE, OF INDIANAPOLIS, INDIANA.

CONTROLLER FOR AUTOMATIC MUSICAL INSTRUMENTS.

1,146,574.

Specification of Letters Patent. Patented July 13, 1915.

Application filed January 30, 1911. Serial No. 605,409.

To all whom it may concern:

Be it known that I, ALEXANDER JAMESON, a citizen of the United States, residing at Indianapolis, in the county of Marion and State of Indiana, have invented a new and useful Controller for Automatic Musical Instruments, of which the following is a specification.

At the present time player pianos and automatic player attachments for pianos are quite common. These devices comprise means by which the sound-producing members may be individually operated upon, said means being controlled by a perforated 10 music sheet; means by which the speed of travel of the music sheet may be controlled; means by which the force exerted upon the sound producing members may be varied; and, in many instances, means by which the 15 sustaining pedal may be operated. In most of these devices, the speed of the sheet motor and the force exerted upon the sound producing members are controlled by manual manipulation of elements of the mechanism especially provided for that purpose, and the motive power is produced by means 20 of pedals and air bellows operated by the feet of the operator, although in some instances the necessary air vacuum or air blast 25 is automatically produced. There are some instances also of mechanism of this general type in which the sound producing devices are electrically operated and controlled by a traveling music sheet located in an instrument 30 separate from the piano and connected thereto only by a cable so that this music sheet instrument may be placed at a point distant from the piano. So far as I am aware, however, all of these devices, 35 if they are capable of producing music with any proper "expression", must be manipulated in some manner by an operator and the manipulation thereof requires a sitting posture of the operator relative to that portion 40 of the mechanism which carries and operates the perforated music sheet, and, consequently, it is impossible for the operator to assume a proper singing position before an audience and at the same time properly 45 manipulate the mechanical operator for the piano.

The object of my present invention is, therefore, to produce a simple and compact instrument which may be readily held in 50 and manipulated by one hand and is of

such character that, when associated with other elements forming also a part of my invention, will serve to control the speed, force and quality of sound production of the musical instrument so that a singer may 60 appear in the usual singing posture before an audience and be able to produce a desired accompaniment to the song, entirely under his own control.

My invention also comprises means by 65 which the singer may be automatically notified of the approach of any particular portion of the traveling perforated music sheet to its coöperating tracker board.

The accompanying drawings illustrate my 70 invention.

Figure 1 is an elevation, full size, of the hand implement forming part of my invention; Fig. 2 an enlarged section on a plane parallel with the elevation of Fig. 1; 75 Fig. 3 an end elevation of one of the valve motors; Fig. 4 an elevation of a means for operating a sustaining pedal, and Fig. 5 a diagram showing the perforated sheet and its tracker board; the sheet motor; the valve 80 and valve motor for controlling the sheet motor speed; the valve and valve motor for controlling the force with which the sound producing mechanisms are operated, etc.

No attempt has been made to illustrate the 85 sound-producing mechanisms for the reason that they may be of any desired type and the general construction thereof is now well understood.

In the drawings, 10 indicates the implement to be held in one hand of the singer-operator. The external shape of this instrument may, of course, be varied to a considerable extent but the form shown has proven in practice to be a convenient one. 90 Pivoted to one side of body 10 is a lever 11 carrying an insulated bridge piece 12 adapted, when the instrument is grasped in the hand, to automatically bridge the two terminals 13 and 14 through which the main 95 electric circuit leads. The terminal 13 is connected by a wire 13' with the battery or other electrical source 61. Projecting from one side of casing 10 is a plunger 15 which is normally urged outwardly by a 100 spring 16, said spring being considerably stronger than spring 17 which normally holds lever 11 in such position that bridge piece 12 is out of contact with terminals 13 and 14. Plunger 15 is provided with a 105 110

finger piece 18, by means of which it may be readily manipulated against the action of spring 16, and said plunger carries a terminal finger 19 which is constantly in circuit with a wire 21 which is connected to terminal 14 and to the metal plate which supports the plunger. Finger 19 is arranged to traverse successively a plurality of terminals 23, each of which is connected to 10 its particular wire 24 forming a part of cable 22.

Rotatably mounted in the upper end of body 10, is a finger piece 31 which carries a terminal finger 32 in constant electrical connection with a wire 33 which is connected to terminal 14. The terminal 32 is adapted to successively contact with terminals 34 each of which is connected to its particular wire 35, which wires also form a part of 20 the cable 22. A spring 36 connected to the finger piece 31 and to the body 10 serves to normally carry the finger piece 31 and the terminal 32 to the initial position shown in the drawings.

At the upper end of body 10 I provide a lamp socket 37 in which I mount a very small electric lamp 38, said lamp being connected to wires 39 and 41 which also form a part of cable 22. Also mounted within body 10 are two terminals 42 and 43, respectively, which are connected to wires 44 and 45, said wires also forming a part of cable 22. The terminals 42 and 43 may be bridged by a bridging piece 46 carried at 35 the inner end of a finger piece 47 arranged near the bottom of the body 10 alongside of plunger 15 and normally held in its outer position by a spring 48. This hand piece which I have just described, in the form 40 shown in the drawings, is intended to be grasped in one hand with the lever 11 in the hollow of the hand and the lamp socket and finger piece 31 projecting upwardly, the thumb encircling the lamp socket and engaging the finger piece 31, while the first and third fingers grasp the main body upon 45 opposite sides of plunger 15. This leaves the middle finger free to engage and manipulate the finger piece 18 and the little finger 50 free to engage the finger piece 47.

In the form of apparatus indicated in the diagram Fig. 5, the perforated music sheet 51 is intended to be driven by the usual wind motor 52 which will be connected in the usual manner by the suction pipe 53 with the air trunk 54, said air trunk having a vacuum maintained within it by any suitable means, such for instance, as a bellows and motor (not shown). The speed of the sheet 60 motor may, as is quite common in the art, be controlled by means of a valve 55 mounted in the suction pipe 53 and the position of this valve is to be controlled by an electric motor, the movable element of which will 65 be moved in accordance with the position of

the terminal finger 32 upon the terminals 34. In order to provide a sensitive electric motor for this purpose, I have provided a rock shaft 56 carrying a plurality of iron cross arms 57 which are set in an angularly progressive manner upon the shaft. In practice I find that approximately a quarter turn of the shaft is sufficient to produce a quarter turn of an ordinary butterfly valve 55 and as many of the cross arms 57 may be provided as may be desired to produce as many different positions of the valve as may be necessary to give the desired number of speeds of the sheet motor. Arranged in position to magnetically affect the several cross bars 57 is a series of electromagnets 58 between the poles of which the cross bars 57 may turn. Each pair of magnets 58 is connected at one side to a wire 59 connected with the source of electrical energy 61. Shaft 56 is connected in any suitable manner, as by pulleys 62, 63 and belt 64 with the valve 55 so that said valve will be shifted in accordance with the movement of the shaft 56.

A motor 65, similar to the valve motor 90 just described, is connected by belt 66 with a valve 67 mounted in the suction pipe 68 which leads from the trunk 54 to a pneumatic action 69 which will operate the sound-producing devices of the piano, the 95 position of the valve 67 determining the force with which said pneumatic action will operate upon the sound producing devices when set in motion by movement of the perforated music sheet.

The several magnets 58 will be connected each by its particular wire 35 with a terminal 34, the several magnets being connected in succession to the successive terminals. The several magnets of motor 65 are connected by a wire 72 with the battery 61 and they are each connected by their particular wire 24 with the terminals 23. Wire 39 is connected to one side of battery 61 while wire 41 leads to a metallic plate 75 mounted upon but insulated from the tracker board 76 beneath the line of travel of the perforated sheet 51. The wearing face of the tracker board 76 is metallic and therefore I connect this wearing face with that 115 side of battery 61 opposite the wire 39 and, in order that the movement of the sheet 51 may automatically close the circuit of the lamp 38, I provide said sheet at desired points with metallic bridging portions 77 which are adapted to electrically connect the insulated plate 75 and the tracker board 76. In practice I find that this bridging member 77 may be very readily formed by the attachment of a very thin piece of metal foil 125 to the under face of the perforated music sheet.

In order to operate the sustaining pedal I provide an electric motor 81 adapted to operate upon valve 82 controlling a pneumatic 130

motor 83 connected with the sustaining pedal mechanism, and this motor 81 is connected with the battery 61 through wires 44 and 45, terminals 42 and 43, and bridging piece 46. If desired, the wires connected to terminals 13 and 14 may lead to the vacuum producing motor (not shown).

The cable 22 will be comparatively small and inconspicuous and of such length as to make it possible for the hand piece 10 to be carried to a considerable distance from the piano. The piano may be placed to one side of a stage and a proper perforated sheet 51 having been placed in initial position in the player mechanism, the singer-operator may occupy the center of the stage facing the audience with the hand piece 10 held in an inconspicuous manner in one hand. As soon as the hand piece is grasped, the lever 11 will yield so as to swing the bridge piece 12 into contact with terminals 13 and 14 and thus electrically connect the various portions of the apparatus to the battery and so as to start the suction producing motor, if that motor has been connected in the manner suggested. Thereupon the sheet motor will start forward at its slowest speed, the valve 55 being in one extreme of its position, and valve 67 will be in one extreme of its position so that either the greatest or the least force will be available to operate the sound producing mechanism. By manipulating the thumb piece 31, the shaft 56 of the valve motor which controls the sheet motor or valve 55, may be quickly shifted so as to produce a practically instantaneous effect upon the speed of the sheet motor and, by a manipulation of the plunger 15, the valve 67 may be shifted so as to obtain proper driving effect upon the sound producing devices. The perforated sheet may be of such character that the singer should begin his performance either with the first chord or at some other time and, in order that proper notice may be given to the singer of the movement of the music sheet, the metal portions 75 of the music sheet will be so placed as to cause a lighting of the lamp 38 at proper intervals and thus advise the performer of the movement and position of the music sheet so that he may be prepared at any time to properly perform.

Where my apparatus is used by a singer in practising, it is desirable that the singer be able to reverse the movement of the music sheet in order to retrace particular passages and in order to accomplish such an operation, the hand piece is provided with a plunger 91 which may be thrown into position to connect a pair of terminals 92 and 93 which are connected to wires 94 forming a part of cable 22 and these wires are in circuit with a small motor 95 like motor 81 and arranged to control a pneumatic motor 96, said pneumatic motor operating upon the revers-

ing lever 97 of the driving train 98 between the sheet motor 52 and the sheet rolls.

I claim as my invention:

1. A hand-piece manipulator for mechanical musical instruments consisting of a main body formed for reception in one hand of an operator, a rotatably movable finger-piece carrying an electric terminal, a series of terminals coöoperative with said finger-piece terminal, a finger-piece movably mounted in said body and carrying an electric terminal, a series of terminals coöoperative with said finger-piece terminal, a main circuit controlling lever movably mounted upon the main body in opposition to one of said finger-pieces, and circuit terminals controlled thereby, a light spring for normally moving said lever in one direction, and a heavier spring for normally moving the said opposition finger-piece in one direction. 80

2. A hand-piece manipulator for mechanical musical instruments consisting of a main body formed for reception in one hand of an operator, a rotatably movable finger-piece carrying an electric terminal, a series of terminals coöoperative with said finger-piece terminal, a finger-piece movably mounted in said body and carrying an electric terminal, and a series of terminals coöoperative with said finger-piece terminal. 95

3. A hand-piece manipulator for mechanical musical instruments consisting of a main body formed for reception in one hand of an operator, a movable finger-piece carrying an electric terminal, a series of terminals coöoperative with said finger-piece terminal, a finger-piece movably mounted in said body and carrying an electric terminal, a series of terminals cooperative with said finger-piece terminal, a main circuit controlling lever 100 movably mounted upon the main body in opposition to one of said finger-pieces, and circuit terminals controlled thereby, a light spring for normally moving said lever in one direction, and a heavier spring for normally moving the said opposition finger-piece in one direction. 110

4. A hand-piece manipulator for mechanical musical instruments consisting of a main body formed for reception in one hand of an operator, a movable finger-piece carrying an electric terminal, a series of terminals cooperative with said finger-piece terminal, a finger-piece movably mounted in said body and carrying an electric terminal, and a series of terminals coöoperative with said finger-piece terminal. 115

5. A hand-piece manipulator for mechanical musical instruments consisting of a main body formed for reception in one hand of an operator, a rotatably movable finger-piece carrying an electric terminal, a series of terminals coöoperative with said finger-piece terminal, a finger-piece movably mounted in said body and carrying an electric ter- 120

and distant connection with a mechanical musical instrument for controlling said instrument, said hand-piece manipulator comprising controlling members for finger-manipulation to control movements of members of the said instrument, and also comprising an electrical indicator, and an electric circuit extending from said indicator, said circuit being designed for connection to a suitable source of energy and to a pair of insulated terminals over which the music sheet of the instrument travels, whereby a metal-

lic bridging member secured to and carried by said music sheet will temporarily close the circuit to operate said indicator.

15

In witness whereof, I, ALEXANDER JAMESON have hereunto set my hand and seal at Indianapolis, Indiana, this 28th day of January, A. D., one thousand nine hundred and eleven.

ALEXANDER JAMESON. [L. S.]
